US00D567140S

(12) **United States Design Patent** (10) Patent No.: **US D567,140 S**
(45) Date of Patent: **** Apr. 22, 2008**

(54) **STAR-TRILLION SHAPED DIAMOND OR
SIMILAR ARTICLE**

(75) Inventor: **Roni Rydlewicz**, Brussels (BE)

(73) Assignee: **Sundiamond USA, Corp.**, New York,
NY (US)

(**) Term: **14 Years**

(21) Appl. No.: **29/279,649**

(22) Filed: **May 4, 2007**

(51) LOC (8) Cl. **11-01**

(52) U.S. Cl. **D11/90**

(58) Field of Classification Search **D11/1-2,**
D11/26-29, 89-92; 63/26-28, 32

See application file for complete search history.
